(57) **CLAIM**

The ornamental design for the radiator filler neck with integrated drip tray assembly, as shown and described.

DESCRIPTION

FIG. 1 is a front perspective view of a radiator filler neck with drip tray assembly lugs showing my new design;

FIG. 2 is a front elevation view thereof;

FIG. 3 is a rear elevation view thereof;

FIG. 4 is a right side elevation view thereof;

FIG. 5 is a left side view thereof;

FIG. 6 is a top plan view thereof; and,

FIG. 7 is a bottom plan view.

In the drawings, the broken lines depict unclaimed subject matter only and form no part of the claimed design.
